UNITED STATES PATENT OFFICE.

HEINRICH SCHIEFERSTEIN, OF BERLIN-CHARLOTTENBURG, GERMANY.

CONTROLLING DEVICE FOR CLOCKWORKS AND THE LIKE.

Application filed March 1, 1923, Serial No. 622,162, and in Germany July 17, 1922.

Time mechanisms, operated by an oscillating system such as pendulums or balance wheels are regulated by changing the effective lengths of the pendulums or by ad-

a flat spring k_2 and the primary pendulum a_1 is driven from the clock-work w by means of the crank g , the rod h_1 and the flat spring k_1 .
60

5 justing the effective length of the springs of the balance wheels, and it is also known that these mechanisms are constructed to automatically compensate for differences due to change in temperature.

I have diagrammatically shown a conventional clock work w one of the wheels of which is provided with a crank pin g connected by rod h_1 to bent leaf spring k_1 , substantially U-shaped, by a connection y_1 65

10 The present invention relates to method and means for regulating time mechanisms operated by one or more oscillating systems in order to obtain the highest degree of free oscillation, to dispense with the usual

adjustable (Figs. 1, 2 and 4) along one leg of the spring. The other leg of the spring is connected to the rod of the main pendulum a_1 by means of a similar adjustable connection x_1 . To the main pendulum a_1 is pivoted 70

15 escapement mechanisms to simplify the construction of such time mechanisms, to permit ready adjustment and to obtain noiseless movements.

To the main pendulum a_1 is pivoted at 4 (Fig. 4) the connecting rod h_2 which is pivoted at 5 to the connection k_2 adjustable along one leg of the U-shaped spring k_2 . The other leg of the spring k_2 is similarly 75

20 oscillating system for watches and clock-works which possesses the greatest possible exactness of working and the oscillation number of which can be varied within wide limits.

25 The drawings show by way of example embodiments of my invention in Figures 1 and 2, Figure 3 is a diagrammatic view of the curves illustrating the working of the invention principle and Figure 4 shows a modification of Fig. 1.

30 Assuming that a relatively inexactly constructed and operating clock-work is to be controlled by an oscillating system, for instance, a pendulum, of course the load imposed on this system by the clock-work will 80

35 be larger the more inexact the construction of the clock-work and the more irregular its working is. But, by coupling as shown in Figure 1, a secondary pendulum a_2 with the highly loaded primary pendulum a_1 , the 85

40 secondary pendulum a_2 has only to compensate the irregularities of the primary pendulum a_1 provoked by the clock-work. This compensation can be effected by means of a considerably smaller quantity of energy than

45 the compensation of the irregularities of the clock-work and, consequently, the second oscillating system may be coupled much looser than the first system. By means of such a combination of two coupled oscillating systems a very high exactness of working can be obtained for the clock-work mechanism 95

50 to be controlled.

55 The two pendulums a_1 and a_2 , Fig. 1, are suspended at c_1 and c_2 and are coupled together by means of a connecting rod h_2 , and an elastic coupling member for instance 100

only on the preciseness of the working of the oscillating system, when providing a coupled oscillating system according to the invention.

Figure 2 shows that the secondary pendulum a_2 is not syntonized but distuned to the primary pendulum a_1 which, for this purpose, is longer than the pendulum a_2 . The two pendulums are coupled together by the rod h_4 in the manner shown in Figure 2 and the primary pendulum a_1 is driven from the clock-work by means of the crank g , the rod h_1 , and the flat spring k_1 as in the case of Figure 1.

The secondary pendulum a_2 swings more rapidly than the primary pendulum a_1 and consequently a certain quantity of energy flows from the primary to the secondary pendulum whereby the latter is caused periodically to oscillate, these oscillations coming to rest always again after few amplitudes. When the primary pendulum a_1 is retarded from time to time by any irregularity of the clock-work mechanism, it swings more slowly, that is to say, it seems to become longer and to withdraw from the resonance position. Thereby the quantity of energy passing from the primary to the secondary pendulum decreases so that, on the other hand, the primary pendulum becomes unloaded to a corresponding degree.

On the contrary, when the resistance of the clock-work mechanism decreases, the first pendulum obtains a larger quantity of driving energy, swings more rapidly and, in a manner, becomes shorter. Consequently this pendulum approaches to resonance position and transmits a larger quantity of energy to the secondary pendulum. Thus a diminution or an augmentation of the resistance of the secondary pendulum counteracts each augmentation or diminution, respectively, of the clock-work resistance.

In Figure 3 the curve R in full lines designates the resonance curve of the primary pendulum. When a variation of the resistance of the clock-work takes place the resonance curve is displaced, for instance, in the position R_1 when the clockwork runs more rapidly and in the position R_2 when the clock-work runs more slowly. If, at normal running, for instance, the energy amount E is transmitted from the first to the secondary pendulum, the transmitted energy has the value E_1 in the case of an increasing speed and the value E_2 in the case of a decreasing speed of running. Thus, when the secondary pendulum is distuned relatively to the first pendulum to a suitable degree by adjusting its variable length correspondingly, an absolutely regular working of the first pendulum is obtained by the action of the secondary pendulum coupled therewith.

Furthermore the principle of distuning according to Figure 1 may be employed also

for two oscillating systems coupled by means of an elastic member or by other means as, for example, as shown in Fig. 1, which can be done by adjusting the bob of the secondary pendulum or pendulums. The coupling member is adjustable so as to be enabled to vary the transmission of energy. Instead of one secondary pendulum, two or more secondary oscillating systems may be provided.

Of course the invention is applicable not only to watches and clock-works but also for controlling other mechanisms by means of oscillating systems. It will thus be seen that I provide two or more oscillating systems one of which, the primary system, receives driving impulses and the other or others influence the operation of the primary system either directly or indirectly; directly by being connected thereto or indirectly coupled or influenced by mass action, or by both.

What I claim is:—

1. A controlling device for time mechanisms comprising an oscillating system, a clock work to drive the same, a secondary oscillating system, and an elastic connecting member coupling the systems.

2. The combination with a time mechanism, of an oscillating system driven thereby, a secondary oscillating system separate from said time mechanism and a common support for the two systems.

3. A controlling device for time mechanisms comprising a primary oscillating system and a secondary oscillating system, an adjustable elastic coupling means connecting the systems for adjusting the energy transmission from one to the other oscillating system.

4. A device for controlling the running of time mechanisms comprising a primary oscillating system, a clock-work driving the same, a secondary oscillating system oscillating relatively to the first system and coupled mechanically therewith and means to adjust the time of oscillation of said secondary system.

5. A controlling device for time mechanisms comprising a primary oscillating system a secondary oscillating system coupled therewith and means to independently adjust the time of oscillation of said secondary system relatively to the first to diminish the amount of energy transmitted to the secondary oscillating system when oscillation of the primary oscillating system retard and vice versa and a time mechanism controlled by and driving said primary system.

6. A device for controlling the running of time mechanisms comprising an oscillating system, secondary oscillating system distuned relatively to the first and adjustable coupling means connecting these oscillating systems.

7. A device for controlling the running of time mechanisms, comprising an oscillating system, a secondary oscillating system operating relatively to the first system, 5 a support common to the systems, adjustable coupling means connecting the systems and means to adjust the time of oscillation of the respective systems.
8. A device for controlling the running 10 of time mechanisms comprising a primary oscillating system and a plurality of secondary oscillating systems yieldingly coupled with said primary system for correcting said primary system and a clock work arranged to drive said primary system and controlled thereby.
9. In a device for controlling the running 15 of time mechanisms, a primary oscillating system and a plurality of secondary oscillating systems connected in series and yieldingly coupled with said primary system for correcting said primary system and a clock work arranged to drive said primary system and controlled thereby.
- 20 10. In a control for time mechanisms, a plurality of pendulums, resilient means connecting the pendulums, a driving crank mechanism connected to one of the pendulums and a spring interposed in said mechanism, said crank and pendulums operating substantially in synchronism. 30
11. In a control for time mechanisms, a plurality of pendulums resilient means connecting the pendulums a driving crank, a connection including one of the pendulums and crank, and adjusting devices for said resilient means. 35
12. In a device for controlling the running of time mechanisms, an oscillatory system driven from the time mechanism, 40 and at least one secondary oscillating system and means connecting the systems in time correcting relation, said secondary system having no separate driving means.
13. A device for controlling the running 45 of time mechanisms, a primary oscillating system, mechanism to drive said system, a secondary oscillating system coupled to the primary system and receiving its driving impulses therefrom, said secondary system capable of relative movement with respect to said first system.

In testimony whereof I affix my signature.
HEINRICH SCHIEFERSTEIN.
